UNITED STATES PATENT OFFICE

2,256,577

MACHINE FOR MIXING TEXTILE FIBERS

Leland F. Remington, Worcester, Mass., assignor
to Curtis & Marble Machine Company, Worcester,
Mass., a corporation of Massachusetts

Application May 13, 1940, Serial No. 334,822

3 Claims. (Cl. 19—146)

This invention relates to a machine for mixing textile fibers, such as cotton or wool, and in which the operation is in part mechanical and in part pneumatic. A machine of this general type is shown in Truslow Patent No. 1,399,590, issued December 6, 1921.

It is the general object of my present invention to improve the construction of such mixing machines as heretofore known, to the intent that the machine may be simplified in structure and may be more efficient in operation.

With this general object in view, an important feature of the invention relates to the provision of a slow-speed motor direct-connected to rotate the distributor pipe and associated parts.

Other features of the invention relate to improved means for supporting and aligning the motor with the rotating mixing mechanism, and to devices for protecting the moving parts from dirt and lint.

My invention further relates to arrangements and combinations of parts which will be herein-after described and more particularly pointed out in the appended claims.

A preferred form of the invention is shown in the drawings, in which

Fig. 1 is a side elevation of my improved machine;

Fig. 2 is an enlarged side elevation of the driving motor and associated parts;

Fig. 3 is a plan view of a supporting ring, looking in the direction of the arrow 3 in Fig. 2; and

Fig. 4 is a sectional end elevation, taken along the line 4—4 in Fig. 1.

Referring to Fig. 1, I have shown a stationary supply pipe 10 having a down-turned delivery portion 11 which extends loosely into a circular opening 12 in the arm 13 of a frame member 14. The member 14 is mounted on angle iron bars 15, which bars in turn are secured by U-shaped castings 16 to an upper turn-table plate 17. The axis of the turn-table plate 17 is in alignment with the opening 12 in the arm 13 and also with the delivery portion 11 of the fixed supply pipe 10.

A distributor pipe 20 is secured to the bars 15 by clamps 21, and one up-turned end 22 of the pipe 20 is secured in the arm 13 in alignment with the opening 12 and with the supply pipe portion 11. The other end 24 of the pipe 20 is up-turned and open, and is in substantial alignment with a deflector plate 26, supported on an arm 27 extending radially from the frame member 14. A counterbalance weight W is provided on the bars

15 to offset the unbalanced weight of the distributing pipe 20 and associated parts.

The entire structure thus far described, with the exception of the fixed supply pipe 10, is slowly rotated so that fibers blown through the supply pipe 10 and distributor pipe 20 will be uniformly distributed and thoroughly mixed as the outlet portion 24 describes a wide circle and as the fiber is simultaneously deflected in all directions by the plate 26.

The general operation of the machine as thus far described is similar to the disclosure of the Truslow patent cited and in itself forms no part of my present invention, which relates more particularly to the means for supporting and rotating the fiber distributing devices.

In my improved construction, I provide a tubular post or stand 30, which may be secured to the bottom of the mixing chamber in any convenient manner, and which supports a collar 31 having arms 32 with inwardly projecting upper ends 33 and with an intermediate stiffening band or ring 34. Brackets 35 are bolted to the inside faces of the arms 32 and support a steel ring or plate 37, on which a vertically disposed motor M is mounted.

The casing 40 of the motor M passes freely through the plate 37 and has a circular flange 41 which rests on said plate and is secured there-

30 to by screws 42.

The drive shaft 45 of the motor M extends loosely through a fixed bearing plate 46 and is secured in the hub 47 of the turn-table plate 17. The bearing plate 46 is secured by bolts 48 to the inwardly projecting ends 33 of the fixed arms 32. A plurality of balls 50 are positioned in a ball race between the plates 17 and 46, and the entire rotating structure is supported by and rotates on this annular ball bearing.

40 The motor M is preferably provided with self-contained reduction gearing, so that the drive shaft and distributor pipe rotate at a lower speed than the rotor of the motor. A casing C encloses the motor M and its associated parts and effectively excludes dirt and lint from the motor and from the ball bearing support of the distributor pipe.

45 I have thus provided an extremely simple but efficient construction for operating a mixing machine, which construction permits an entirely uniform distribution of fibers about the post or stand 30, with no obstructing parts to interfere with free fall of the fibers.

Having thus described my invention and the 50 advantages thereof, I do not wish to be limited

to the details herein disclosed, otherwise than as set forth in the claims, but what I claim is:

1. In a mixing machine having a fixed supply pipe, a rotating distributor pipe and a deflecting plate, that improvement which comprises providing a fixed supporting frame, a ring plate mounted on said frame, an electric motor projecting loosely downward through the opening in said ring plate and secured in vertical position to the top face thereof, means to directly connect the drive shaft of said motor to the rotatable structure comprising said distributor pipe and its associated parts, said structure having an upper bearing plate, said supporting frame having a lower and fixed bearing plate, and a plurality of balls being interposed between said plates and forming a self-centering antifriction bearing for said rotating structure.

2. In a mixing machine having a fixed supply pipe, a rotating distributor pipe and a deflecting plate, that improvement which comprises providing a fixed supporting member, a supporting frame mounted on said member, a ring plate secured on said supporting frame, an electric motor projecting loosely downward through the opening in said ring plate and secured in vertical position to the top face thereof, the rotatable struc-

ture comprising said distributor pipe and its associated parts being aligned with and directly connected to the drive shaft of said motor and having an upper bearing plate, said supporting frame having a lower and fixed bearing plate, and a plurality of balls being interposed between said plates and forming a self-centering anti-friction bearing for said rotating structure.

3. In a mixing machine having a fixed supply pipe, a rotating distributor pipe and a deflecting plate, that improvement which comprises providing a fixed vertically extending supporting frame, an electric motor suspended within the upper portion of said frame with its axis vertical and having a peripheral flange resting on and secured to supporting portions within said frame and substantially below the top surface thereof, said frame being arranged circumferentially about said motor, a bearing mounted on top of said frame for supporting the rotatable structure which comprises the distributor pipe and its associated parts, the axes of said motor and of said rotatable structure being aligned with each other, and a direct driving connection between the driving shaft of said motor and said rotating structure.

LELAND F. REMINGTON.
